(57) **CLAIM**

The ornamental design for an extended cab wind deflector, as shown and described.

DESCRIPTION

FIG. 1 is a perspective view of an extended cab wind deflector, showing my new design;

FIG. 2 is a front view thereof;

FIG. 3 is a left side view thereof, the opposite side being the mirror image;

FIG. 4 is a top view thereof; and,

FIG. 5 is a rear view thereof.

The broken lines in the drawings are for illustrative purposes only and form no part of the claimed design.
